CLAIM

The ornamental design for a drinking vessel with stones, as shown and described.

DESCRIPTION

FIG. 1 is perspective view of a drinking vessel with stones showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines shown in the figures represent unclaimed portions of the drinking vessel and form no part of the claimed design.
